SAFETY VALVE UNIT

Charles M. Bailey and William J. Turner,
San Francisco, Calif.

Application December 16, 1940, Serial No. 370,310

7 Claims. (Cl. 137—153)

This invention comprises in general an improvement in safety valves, and in particular the invention is directed to a novel form of safety valve unit primarily designed for use in connection with gas fired water heaters and like apparatus.

Domestic hot water heaters are commonly provided with automatic temperature regulators which normally function to maintain the water in the tank at a predetermined temperature. However, these automatic regulators sometimes fail to function, whereupon the water in the tank reaches boiling point and the resultant steam pressure may cause an explosion of the heater.

It is therefore the principal object of this invention to provide a safety valve unit adapted to be interposed in the gas feed pipe of a water heater and operative upon occurrence of abnormal pressure conditions in the water tank to shut off the flow of gas through said pipe.

Another object of the invention is to provide a safety valve unit, as above, including adjustable means to set the unit to operate at a predetermined abnormal pressure.

A further object of the invention is to provide snap action closing of the safety valve; such snap action movement being effected by suitable mechanism actuated by a pressure responsive element.

It is also an object of the invention to provide a safety valve unit designed for ready connection with conventional water heaters.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

In the drawing similar characters of reference indicate corresponding parts in the several views:

Figure 1 is a sectional elevation of the unit illustrating the valve assembly in open position.

Figure 2 is a sectional elevation of the unit illustrating the valve assembly in closed position.

Referring now more particularly to the characters of reference on the drawing, the safety valve unit comprises a body 1 formed with spaced internal chambers, indicated at 2 and 3 respectively; such chambers opening to opposite ends of the body and being threaded adjacent their outer ends for the reception of adjacent ends of the gas feed pipe 4 in which the unit is adapted to be interposed.

The unit is interposed in the gas feed line so

that the gas flows first into chamber 3, and from chamber 3, the gas flows upward through a port 3a into an enclosed hood or housing 5. This housing is initially open at the bottom, but is secured in sealed relation with the top of body 1 by means of a gasket 6 being interposed between the housing and said body. From the housing 5, the gas flows downward through a valve seat 7 into chamber 2 and thence out into the gas feed pipe in the direction of the burner of the water heater.

A disc valve 8 cooperates with valve seat 7 and is carried by valve stem 9 which extends through a spider 10 centrally of the valve seat and through the bottom of the body below chamber 2. In its normal position, valve 8 is open relative to valve seat 7 as shown in Fig. 1.

The lower end of valve stem 9 projects into a downwardly opening socket 11 formed on the body, and into which socket a plug 12 is threaded; there being an inverted, cup-like flexible diaphragm D secured in the socket 11 inwardly of plug 12, whereby to prevent gas from escaping by valve stem 9 and out of the socket when plug 12 is removed.

The valve 8 is normally maintained in open position by means of a snap-action toggle link assembly constructed as follows: A pair of rigid posts 13 are mounted in upstanding position on the body within housing 5, and on opposite sides of the vertical plane of valve stem 9. A lever 14 is pivoted intermediate its ends as at 15 on the upper end of one of the posts 13, for swinging movement in a vertical plane. A compression spring 16 is pivoted at one end on the upper end of the other post 13 as at 17, while the adjacent ends of lever 14 and compression spring 16 are fitted with a pin and cup toggle 18; the lever 14 and spring 16 sloping upwardly toward each other when the valve is open. A link 19 is pivotally connected at 20 to lever 14 adjacent the toggle 18 and depends therefrom to pivotal connection at 21 with the upper end of valve stem 9 above valve 8.

In order to trip the snap action toggle link assembly downward beyond a horizontal plane and to a valve closing position, and when abnormal pressure conditions occur in the hot water tank of the water heater, I provide the following instrumentalities: The body 1 between chambers 2 and 3 is formed with a passage 22 therethrough; the lower end of said passage being threaded for connection with a pipe 23 leading from the top of the water tank 24 of the water heater. At its upper end, passage 22 is threaded for the re-

ception of the lower end of the hollow base 25 of a Bourdon tube 26 which extends from the upper end of said base on a curve to a point adjacent but above the snap action toggle link assembly. From such point, the Bourdon tube is fitted with a projecting arm 27 which terminates some distance above the end of lever 14 which is opposite toggle 18. A pin 28 projects laterally from lever 14 adjacent said end, and rides in a vertically elongated slot 29 in a link 30 suspended from the free end of arm 27 by means of an adjustment screw 31.

Operation

When the temperature regulator of the water heater is operating normally, the several elements of the safety valve unit are disposed in the position shown in Fig. 1. However, should the temperature regulator fail to function properly and the water be heated excessively and steam pressure created, such pressure passes through pipe 23, base 25 and thence into the Bourdon tube 26. When this occurs, the Bourdon tube expands, causing the free end of arm 27 to rise, carrying with it link 30 which in turn trips the snap action toggle link assembly downward, causing valve 8 to close with valve seat 7. This shuts off the flow of gas in the gas feed pipe 4, and prevents further heating of the water in tank 24; thus providing adequate safety against explosion of the tank. When the snap action toggle link assembly is tripped downward, the pin 28 rides up in slot 29 and no strain is placed on tube 26.

Once the safety valve unit has actuated and the valve closed, it must be manually reset. This is accomplished by removing plug 12 and depressing the inverted cup-like diaphragm D upwardly until the lower end of valve stem 9 is engaged and forced upward, effecting an opening of valve 8 from valve seat 7, as well as an upward snap action of the toggle link assembly, and a return of pin 28 to the lower end of slot 29.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention, what we claim as new and useful and desire to secure by Letters Patent is:

1. A pressure actuated valve unit comprising a body having spaced chambers therein open to the exterior of the body and threaded for reception of ends of pipe, means forming a passage between said chambers, a normally open valve mounted in said passage, normally inactive means to close said valve, and other means responsive to abnormal pressure conditions operative to actuate said normally inactive means, said first named means including a housing removably mounted on and enclosing one face of the body, the valve and said normally inactive valve closing means being outwardly of said face of the body and being enclosed within the housing.

2. A pressure actuated valve unit including a normally open valve, a snap action toggle link assembly mounted adjacent but spaced from the valve, a link pivotally connected between the

assembly and the valve and arranged to close the valve upon snap action movement of the assembly to one position and to open the valve upon snap active movement of the assembly to another and normal position, a Bourdon tube responsive to abnormal pressure conditions mounted adjacent and means operatively connecting said tube and said snap action toggle link assembly, said tube being operative to effect snap action movement of said assembly to said one position, and said means comprising a longitudinally slotted link depending from the free end of the tube, said end of the tube being disposed above the assembly and adjacent one end thereof, the corresponding lever of the assembly being extended beyond its pivot in a direction away from the assembly and a horizontal pin projecting from said portion of the lever and normally engaging in the bottom of the slot

20

3. A pressure actuated valve unit including a normally open valve, means to close said valve, other means responsive to abnormal pressure conditions operative to actuate said first named means, and a manually actuated element to open said valve; the valve unit including a body, and said element being a valve stem rigid with the valve and slidably projecting through and extending beyond the body, an outwardly opening socket formed on the body and surrounding and completely enclosing the projecting portion of the valve stem, and a removable plug in and closing the outer end of the socket.

4. A pressure actuated valve unit comprising a body having spaced chambers therein open to opposite sides of the body and threaded for the reception of ends of pipe, a housing mounted on and enclosing a portion of the exterior of the body, the body having ports therethrough from said chambers into said housing, a valve mounted on the body and arranged to close one of said ports, the valve being accessible from within the housing, a normally inactive snap action toggle link assembly mounted in the housing in connection with said valve and arranged to close the latter, and a Bourdon tube disposed in the housing and connected with said assembly to actuate the same upon expansion of the tube, the body having a passage therethrough from within the housing, and the base of the tube being mounted in communication with the inner end of said passage, the outer end of said passage being adapted for connection in communication with a source of pressure.

5. A pressure actuated valve unit comprising a body having spaced chambers open at one end for connection with pipe ends and having ports open to one face of the body, a housing removably mounted on and enclosing said one face and the ports, one port within the housing having a surrounding valve seat, a normally open valve to cooperate with said seat, normally inactive valve closing means within the housing, and other means in the housing responsive to abnormal pressure conditions to actuate said normally inactive means.

6. A device as in claim 5, including a flexible cupped airtight diaphragm disposed in the socket over and clear of the adjacent end of the stem and sealed about its periphery in the body inwardly of the plug.

7. A pressure actuated valve unit comprising a body, a housing over and enclosing one face of the body, a pair of longitudinally separated chambers in the body having their opposite ends

open to opposite sides of the body and adapted for connection to pipe ends, the chambers having ports communicating with said one face of the body, a normally open valve within the housing to cooperate with one port, normally inactive means in the housing to close the valve and pressure actuated means in the housing to operate

5

said normally inactive means; the body having a passage therethrough between the chambers and extending to said one face of the body and to which the pressure means is connected.
